UNITED STATES PATENT OFFICE.

ALBERT LEGG, OF ALLENDALE, NEW JERSEY.

HYDRAULIC ENGINE.

SPECIFICATION forming part of Letters Patent No. 716,254, dated December 16, 1902.

Application filed January 18, 1901. Serial No. 43,711. (No model.)

To all whom it may concern:

Be it known that I, ALBERT LEGG, a citizen of the United States of America, residing in the town of Allendale, county of Bergen, and 5 State of New Jersey, have invented certain new and useful Improvements in Water or Hydraulic Engines, of which the following is a specification, reference being had therein to the accompanying drawings.

10 My invention relates to water or hydraulic engines; and its objects are to provide a simple and inexpensive means of developing power from a moving column of water and to render such means readily adjustable to existing systems of water-supply.

To these ends my invention consists of a box or chamber adapted to receive and hold the water from a moving column thereof, two hollow cylinders communicating with said 20 chamber and the atmosphere, devices connected with said cylinders upon which the water supplied to the chamber may operate, and means of transmitting the power developed by said devices to a revolving shaft.

25 An application of my device is illustrated in the accompanying drawings, in which similar figures of reference indicate similar parts throughout the various views, of which—

Figure 1 is a sectional view on the line 1 1 30 of Fig. 2. Fig. 2 is a side elevation, partly broken away. Fig. 3 is an enlarged detail view, and Fig. 4 is a sectional view on line 4 4 of Fig. 3.

35 1 is a pipe leading into chamber 2, the pipe and chamber being constructed of sufficient strength to withstand the pressure under which the water is received by pipe 1.

40 3 and 4 are two hollow cylinders, each firmly secured to the chamber 2 and at one end communicating with the interior thereof and at the other end with the atmosphere. The communication of cylinder 3 with the atmosphere is shown in the drawings by discharge-pipe 5 and that of cylinder 4 by vent 45 6. Such communication might be had, however, by simply leaving the outside ends of the cylinders open.

7 7 are supports for shaft 8, upon which are two cranks 9 and 10. Operatively connected with crank 9 is a jointed rod 11. Upon rod 11 is an abutment 13.

14 is a cover sufficient to cut off communica-

cation between chamber 2 and cylinder 3 and is loosely mounted on rod 11, so that when said cover 14 is forced toward the end of cylinder 3 it will abut against abutment 13 and carry with it rod 11 on crank 9.

15 is a lug on rod 11 to retain cover 14 in position when chamber 2 has no water therein under pressure. Abutment 13 should be 60 adjusted so that cover 14 will close the end of cylinder 3 shortly before rod 11 has completed its stroke in that direction.

Figs. 3 and 4 illustrate a good method of 65 constructing the inner end of cylinder 3. 18 is a shoulder or seat for cover 14, and 19 19 are slides coöperating with grooves on cover 14.

Operatively connected with crank 10 is jointed rod 12, bearing at its other end piston 16, working in cylinder 4.

17 is a wheel upon shaft 8, operating to balance the device. If the wheel is turned so that cover 14 has opened communication between chamber 2 and cylinder 3 and water 75 under pressure is allowed to enter chamber 2, when the same becomes full, or nearly so, the force of the water will push said cover so as to close cylinder 3, and wheel 17 will continue to revolve so long as water is allowed to enter chamber 2 under pressure, the water escaping through discharge-pipe 5. When the pressure of the water has caused cover 14 to close cylinder 3, thus preventing the outflow of water at that point, the pressure, apparently in the nature of a blow, is delivered against the bottom of piston 16, forcing said piston 16 up in cylinder 4, carrying with it rod 12, which being operatively connected with crank 10 causes the shaft 8 85 and carrying-wheel 17 to revolve. This upward movement causes cover 14 to descend, thus releasing water through vent 5. At this point the water-pressure is considerably reduced, so that but little resistance is offered 90 to the descent of piston 16 to a position in which the operation is repeated.

Pipe 1 may be provided with a valve 20 without departing from my invention. 21 is a check for said valve.

What I claim, and desire to secure by Letters Patent, is—

1. A water or hydraulic engine consisting of a chamber adapted to receive and hold wa-

- ter under pressure, two cylinders each communicating with said chamber and with the atmosphere, a piston adapted to operate in one of said cylinders, a cover adapted to close the inner end of the other of said cylinders, a revolving shaft having two cranks thereon, means whereby as said piston is operated one of said cranks is operated, and whereby as said cover is operated, to close communication between said chamber and one of said cylinders the other of said cranks is operated, and means of maintaining a supply of water in said chamber under pressure, substantially as described.
- 15 2. In a water or hydraulic engine, the combination of a chamber adapted to receive and hold water under pressure, two cylinders each communicating with said chamber and with the atmosphere, a piston adapted to operate in one of said cylinders, a cover adapted to close the inner end of the other of said cylinders, a revolving shaft having two cranks thereon, means whereby, as said piston is operated, one of said cranks is operated, and whereby as said cover is operated to close communication between said chamber and one of said cylinders, the other of said cranks is operated; and means of maintaining a supply of water in said chamber under pressure, with a valve adapted to cut off the supply of water when the pressure in the chamber is greater than the pressure of said water-supply, substantially as described.
- 30 3. In a water or hydraulic engine, the combination of a chamber adapted to receive and hold water under pressure, two cylinders each communicating with said chamber and with the atmosphere, a piston adapted to operate in one of said cylinders, a cover adapt-

ed to close the inner end of the other of said cylinders, a revolving shaft having two cranks thereon, means whereby, as said piston is operated, one of said cranks is operated, and whereby as said cover is operated to close communication between said chamber and one of said cylinders, the other of said cranks is operated; and means of maintaining a supply of water in said chamber under pressure, with a balance-wheel mounted on said shaft, substantially as described.

4. In a water or hydraulic engine, the combination of a chamber adapted to receive and hold water under pressure, two cylinders each communicating with said chamber and with the atmosphere, a piston adapted to operate in one of said cylinders, a cover adapted to close the inner end of the other of said cylinders, a revolving shaft having two cranks thereon, means whereby, as said piston is operated, one of said cranks is operated, and whereby as said cover is operated to close communication between said chamber and one of said cylinders, the other of said cranks is operated; and means of maintaining a supply of water in said chamber under pressure, with a valve adapted to cut off the supply of water when the pressure in the chamber is greater than the pressure of said water-supply, and a balance-wheel mounted on said shaft, substantially as described.

In witness whereof I hereunto affix my name, in presence of two witnesses, this 17th day of January, 1901.

ALBERT LEGG.
